UNITED STATES PATENT OFFICE

ROBERT H. GEORGE, OF BROOKLAWN, NEW JERSEY

DRAIN VALVE

Application filed July 29, 1924. Serial No. 728,843.

My invention relates to drain valves for steam apparatus and the like, and it relates more particularly to that type of automatic drain valve which permits the water of condensation to flow from the steam apparatus, the valve member being spring suspended, and in use being normally held on its seat against the tension of the suspending spring by the live steam pressure. My invention also contemplates a drain valve which will also serve as a relief valve in the event of any abnormal pressure existing in the working chambers of the steam apparatus.

The principal object of my present invention is to provide an improved form of valve of the above mentioned type, which will be simple and efficient in its action and relatively inexpensive. A further object of my invention is to provide a valve of said type, of such construction that, when any abnormal pressure exists in the portion of the steam apparatus which the valve is primarily adapted to drain, such pressure will be exerted against the valve member uniformly about the axis thereof, to the end that the raising of the valve from its seat at the proper time will be more certain. A further object of my invention is to provide improved means for guiding the valve member within the casing thereby to preclude jamming of said valve member therein. A further object of my invention is to provide improved means for regulating the tension of the suspending spring. A still further object of my invention is to provide, as a specific embodiment, a duplex type of drain valve, particularly adapted for use in connection with locomotive and the like engines, which will permit the entrapped fluid in the ends of the cylinder of the steam engine to pass freely therethrough when the engine is running with the steam supply shut off, as occurs, for example, when a locomotive engine is "drifting", the construction being such that likelihood of either end of the cylinder of the engine drawing in air through the drain valve will be reduced to a minimum.

The nature and characteristic features of my present invention will be more readily understood from the following description,

taken in connection with the accompanying drawings forming part hereof, in which:

Figure 1 is a vertical central sectional view of a drain valve embodying the main features of my present invention, the valve member being shown in the raised or elevated position assumed when the live steam supply is shut off and the device is draining the water of condensation from the steam apparatus in connection with which the same is used;

Fig. 2 is a top or plan view thereof;

Fig. 3 is a horizontal section thereof, taken approximately on the line 3-3 of Fig. 1;

Fig. 4 is a horizontal section thereof, taken approximately on the line 4-4 of Fig. 1;

Fig. 5 is a view similar to Fig. 1, but showing a duplex type of valve, particularly adapted for use in connection with locomotive engine cylinders;

Fig. 6 is a horizontal section of the device shown in Fig. 5, the section being taken approximately on the line 6-6 of Fig. 5; and

Fig. 7 is a transverse vertical section of the lower portion of said structure, this section being taken approximately on the line 7-7 of Fig. 6.

Referring now more particularly to Figs. 1 to 4 of the drawings, in the particular embodiment of my invention therein shown, 10 is a casing having an internal chamber 11, at the bottom of which there is provided a seat 12 for the valve member 13 which is mounted within the chamber 11. The top of the chamber 11 is closed by means of a bonnet 14, which is preferably threaded in the upper end of the casing 10, a sealing washer 15 being provided and interposed to seal the joint between the bonnet 14 and the casing 10.

Extending from one side of the casing 10 is a threaded nipple 16, having a port or passageway 17, an enlarged portion 18 of which communicates with the valve chamber 11 at the upper portion thereof above the valve member 13 (see Figs. 1 and 3). This connection nipple 16 is adapted to be connected by suitable piping to the steam apparatus which is to be drained of the water of condensation which may have accumulated therein. This connection nipple 16 is preferably and usual-

ly connected with such portion of the said steam apparatus as is normally under live steam pressure only during the operation of the same.

5 Horizontally extending from the lower portion of the casing 10 is a connection nipple 19, which is provided with a port or passageway 20. The port or passageway 20 terminates in an annular chamber 21 in the seat 10 portion 12 of the casing 10. The connection nipple 19 is adapted to be connected by means of suitable piping (not shown) to the working portion of the steam apparatus in connection with which the valve is used, for the purpose 15 of draining therefrom any water of condensation which may accumulate therein.

Projecting downward from the bottom of the casing 10 is a connection nipple 22, having an internal passageway 23 which extends 20 from the bottom of the internal chamber 11 and is adapted to be closed by the valve member 13 when the same is seated, as will be hereinafter more fully explained. The nipple 22 is adapted to be connected to a drain 25 pipe (not shown) for carrying away the water of condensation which is permitted to pass through the device.

The under surface of the valve member 13 is frusto-conical in shape, and the valve seat 30 12 at the bottom of the casing 10 is shaped complementary thereto. This arrangement permits a construction in which there are no pockets in which the condensation water might accumulate and freeze, and thus render the device inoperative in cold weather.

Extending upward from the rim of the valve member 13 is a plurality of vertical arms 24, the exterior surfaces of which are almost complementary to the interior surface 40 of the casing 10, being preferably of a somewhat smaller diameter. The arms 24 serve as a means for guiding the valve member to its seat by preventing the same from tilting during its movement within the casing. 45 The rim of the valve member 13 is also preferably provided with a plurality of notches or recesses 25, whereby any water of condensation which may accumulate thereon, or pass into the interior of the device above the valve member 13, may readily pass below the same when the valve member is in the raised position, as shown in Fig. 1 of the drawings.

50 Mounted in the inner lower central portion of the valve member 13 is a gland-like member 26, being preferably threaded therein, which serves to confine the enlarged or head portion 27 of a bolt 28, the upper end of which is apertured for the engagement thereof by the hook-shaped lower end of a coil 60 spring 29, forming a swivel connection between the spring and the valve to permit the valve to rotate with respect thereto. The hook-shaped upper end of the spring 29 engages an aperture in the lower end of a threaded bolt 30 which extends through a stuffing

box 31 formed in the upper portion of the bonnet 14. The bolt 30 is threaded in the gland 32 of the stuffing box, whereby the same may be adjusted from the exterior to vary the tension of the spring 29, when desired. The 70 stuffing box 31 contains suitable packing 33, which not only serves to prevent the leakage of live steam from the interior of the device, but also serves as a means of frictionally retarding the adjusting bolt 30 against undesired rotation.

The operation of the device as thus far described may now be explained. When the steam apparatus, in connection with which the device is used, is not in operation, and the live steam supply is shut off, the valve member 13 will be held in the raised or elevated position shown in Fig. 1 of the drawings by means of the spring 29, the upwardly extending arms 24 of the valve member 13 serving to limit the upward movement thereof by abutting against the under surface of the bonnet 14. When said valve member is in this upper position, any water of condensation which may collect in the live steam line will 90 pass by means of the piping (not shown), which extends to the connection nipple 16, and will thence be permitted to pass through the passage spaces provided by the notches or recesses 25 in the rim of the valve member 13, as well as in the clearance space between the rim of the valve member 13 and the side walls of the chamber 11, after which the same will pass downward, and through the passageway 23 of the connection nipple 22, to the drain.

Likewise, when the valve member 13 is in the raised or elevated position shown in Fig. 1 of the drawings, any water of condensation which may collect in the working chambers of the steam apparatus may pass through the pipe line which is connected to the connection nipple 19, and thence through the passageway 20 to the annular space 21 in the seat portion of the valve casing, and will thence pass through the passageway 23 of the connection nipple 22 to the drain.

When, however, the live steam pressure is turned on in the apparatus, the flow of the steam into the device will cause the valve member 13 to be carried downward to its seated position, thereby simultaneously closing the passageway 23 which extends to the drain and the annular chamber 21 in the seat portion 12 of the casing. Should, however, any abnormal pressure be created in that portion of the steam apparatus to which the connection nipple 19 is connected, as will occur, for example, when a quantity of water of condensation accumulates therein, this abnormal pressure will be exerted against that portion of the under face of the valve member 13 which is exposed to the annular chamber 21, and thereby the valve member 13 will be raised against the live steam pressure on the 130

upper side thereof, and the condensation water will be permitted to flow through the passageway 23 to the drain, and the pressure relieved.

5 In a similar manner, when the live steam supply is shut off after a period of operation, the pressure remaining in the working chambers will cause the valve member 13 to be raised from its seat, after which it will be held in the raised position, as hereinbefore set forth, until the live steam supply is again turned on.

It will be noted that when the valve is raised the pressure will be exerted uniformly about the axis of the valve member, so that the valve will not tend to tilt and will be more readily raised than is the case with valves of this type in which pressure is exerted on only one side of the axis of the valve member. Furthermore, the arms 24, which extend upward from the rim of the valve member, will further preclude any possibility of the valve member 13 becoming tilted and thereby jamming in the casing, which might prevent the valve from functioning at the proper time to drain the condensation water from the steam apparatus in connection with which the device is used.

Referring now more particularly to Figs. 5 to 7 of the drawings, there is there shown a duplex type of valve which is particularly adaptable for use in connection with locomotive and the like engines, and which will serve not only as an automatic drain and relief valve, but also as a "drifting" valve, which will permit the entrapped fluid in the ends of the cylinder of the engine to pass freely therethrough when the engine is running with the steam supply shut off.

40 In this arrangement, there are provided two valve devices, arranged side by side with their casings 10 joined integrally to each other, there being provided a common live steam connection nipple 16, having a port or passageway 17 with the enlarged portion 18 thereof extending to the respective chambers 11 of each of the valves. There is, however, provided a separate connection nipple 19 for each of said valves, which connection nipples 19 are adapted to be respectively connected to the two ends of the locomotive or other steam engine cylinder. In this arrangement, the drain connection nipple 22 is omitted, but there is formed on the under side of the casing a chamber 35, which is in communication with the lower part of the valve chamber 11 of each of the valve structures, below the seat portion 12 thereof. At each end of the chamber 35, beyond the place of communication with the respective valve chambers, there is provided an outlet aperture 36, preferably arranged on one of the side walls of the chamber 35. In other respects, the construction and arrangement of the respective valve structures are substantially similar to the construction and

arrangement shown in Figs. 1 to 4 of the drawings.

Likewise, the operation of the respective valve structures, comprising the duplex valve shown in Figs. 5 to 7 of the drawings, is similar to that hereinbefore set forth. In this arrangement, however, there is provided an additional function, in that when the engine is "drifting", that is to say, when the steam supply is shut off, both valve members 13 will be raised to the elevated positions shown in Fig. 5 of the drawings, and the entrapped steam in the engine cylinder will then be permitted to pass from one end of the cylinder to the other, back and forth through the chamber 35, and likelihood of sucking air from the exterior will be reduced to a minimum.

It will be seen that by the present invention there is provided an improved form of automatic drain valve, of the type wherein the valve member is normally held on its seat by live steam against the tension of a suspending spring, in which the raising of the valve member will be more certain, whether the same be accomplished by the action of the pressure remaining in the working chambers of the steam apparatus in connection with which the same is used, after the live steam supply is shut off, or whether the valve is forced upward by abnormal pressure in the working chambers; in which the means for regulating the tension of the suspending spring is greatly improved; and which may be readily arranged as a duplex valve for use in connection with locomotive and the like engines, enabling the same to function as an automatic "drifting" valve when the engine is running with the steam supply shut off.

Having thus described the nature and characteristic features of my invention, what I claim as new and desire to secure by Letters Patent is:

1. An automatic drain valve comprising a casing having an internal chamber, a valve member mounted in said chamber, said valve member having its lower working surface of frusto-conical shape and the bottom of the chamber being correspondingly shaped complementary to the valve to form a seat therefor, the rim of the valve member being so shaped with respect to the chamber as to provide a passageway from above the valve member when the same is elevated, a spring adapted to raise the valve member from its seat, a pipe connection member formed on the casing and having a port communicating with the internal chamber above the valve member, the valve seat having an annular chamber formed therein, said annular chamber being closed by the valve member when the same is seated and the arrangement being such that when fluid under pressure is admitted into said annular chamber the pressure tending to raise the valve member from

its seat will be exerted uniformly about the axis of the valve member, a pipe connection member formed on the casing and having a port communicating with the annular chamber in the valve seat, and the device having a drain passageway at the bottom communicating with the interior of the casing at the bottom of the valve seat.

2. An automatic drain valve comprising a casing having an internal chamber, a valve member mounted in said chamber, said valve member having its lower working surface of frusto-conical shape and the bottom of the chamber being correspondingly shaped complementary to the valve to form a seat therefor, the rim of the valve member being so shaped with respect to the chamber as to provide a passageway from above the valve member when the same is elevated, a spring adapted to raise the valve member from its seat, a pipe connection member formed on the casing and having a port communicating with the internal chamber above the valve member, the valve seat having an annular chamber formed therein, said annular chamber being closed by the valve member when the same is seated and the arrangement being such that when fluid under pressure is admitted into said annular chamber the pressure tending to raise the valve member from its seat will be exerted uniformly about the axis of the valve member, a pipe connection member formed on the casing and having a port communicating with the annular chamber in the valve seat, the device having a drain passageway at the bottom communicating with the interior of the casing at the bottom of the valve seat, and a plurality of arms carried by the valve member and extending upwardly from the rim thereof adapted to prevent said valve member from tilting within the casing.

3. An automatic drain valve comprising a casing having an internal chamber, a valve member mounted in said chamber, said valve member having its lower working surface of frusto-conical shape and the bottom of the chamber being correspondingly shaped complementary to the valve to form a seat therefor, the rim of the valve member being so shaped with respect to the chamber as to provide a passageway from above the valve member when the same is elevated, a spring adapted to raise the valve member from its seat, a pipe connection member formed on the casing and having a port communicating with the internal chamber above the valve member, the valve seat having an annular chamber formed therein, said annular chamber being closed by the valve member when the same is seated and the arrangement being such that when fluid under pressure is admitted into said annular chamber the pressure tending to raise the valve member from its seat will be exerted uniformly about the

axis of the valve member, a pipe connection member formed on the casing and having a port communicating with the annular chamber in the valve seat, the device having a drain passageway at the bottom communicating with the interior of the casing at the bottom of the valve seat, a plurality of arms carried by the valve member and extending upwardly from the rim thereof adapted to prevent said valve member from tilting within the casing, and the valve member having a plurality of recesses in the rim thereof forming a passageway to permit drainage from above the valve member.

4. An automatic drain valve comprising a casing having an internal chamber, a valve member mounted in said chamber, the lower surface of said valve member being frusto-conical in shape and the bottom of the chamber being shaped complementary to the valve to form a seat therefor, a pipe connection member extending from one side of the casing and having a port extending to the internal chamber above said valve member, a pipe connection member extending from the side of the casing having a port extending to the valve seat, the device having a drain passageway at the bottom communicating with the interior of the casing at the bottom of the valve seat, a bonnet mounted in the upper portion of the casing, a spring adapted to raise the valve member from its seat, the valve member being suspended from one end of said spring, a bolt to the inner end of which the other end of said spring is secured, and a stuffing box carried by the bonnet through which said bolt extends.

5. An automatic drain valve comprising a casing having an internal chamber, a valve member mounted in said chamber, the lower surface of said valve member being frusto-conical in shape and the bottom of the chamber being shaped complementary to the valve to form a seat therefor, a pipe connection member extending from one side of the casing and having a port extending to the internal chamber above said valve member, a pipe connection member extending to the valve seat, the device having a drain passageway at the bottom communicating with the interior of the casing at the bottom of the valve seat, a bonnet mounted in the upper portion of the casing, a spring adapted to raise the valve member from its seat, the valve member being suspended from one end of said spring, a bolt to the inner end of which the other end of said spring is secured, and a stuffing box carried by the bonnet through which said bolt extends and in a portion of which said bolt is threaded.

6. An automatic drain valve comprising a casing having an internal chamber, a valve member mounted in said chamber, the lower surface of said valve member being frusto-conical in shape and the bottom of the cham-

- ber being shaped complementary to the valve to form a seat therefor, a pipe connection member extending from one side of the casing and having a port extending to the internal 5 chamber above said valve member, a pipe connection member extending from the side of the casing having a port extending to the valve seat, the device having a drain passageway at the bottom communicating with the 10 interior of the casing at the bottom of the valve seat, a bonnet mounted in the upper portion of the casing, a spring adapted to raise the valve member from its seat, the valve member being suspended from one end of said 15 spring, a bolt to the inner end of which the other end of said spring is secured, and a stuffing box carried by the bonnet through which said bolt extends, said stuffing box having a gland member in which said bolt is 20 threaded.
7. An automatic drain valve comprising a casing having an internal chamber, a valve member mounted in said chamber, the lower surface of said valve member being frusto- 25 conical in shape and the bottom of the chamber being shaped complementary to the valve to form a seat therefor, a pipe connection member extending from one side of the casing and having a port extending to the in- 30 internal chamber above said valve member, a pipe connection member extending from the side of the casing having a port extending to the valve seat, the device having a drain pas- 35 sageway at the bottom communicating with the interior of the casing at the bottom of the valve seat, a bonnet mounted in the upper portion of the casing, a spring adapted to raise the valve member from its seat, the valve member being rotatably suspended from one 40 end of said spring, a bolt to the inner end of which the other end of said spring is secured, and a stuffing box carried by the bonnet through which said bolt extends and in a portion of which said bolt is threaded.
- 45 8. An automatic drain valve comprising a casing having an internal chamber, a valve member mounted in said chamber, the lower surface of said valve member being frusto- 50 conical in shape and the bottom of the chamber being shaped complementary to the valve to form a seat therefor, a pipe connection member extending from one side of the casing and having a port extending to the internal chamber above said valve member, a pipe con- 55 nection member extending from the side of the casing having a port extending to the valve seat, the device having a drain passageway at the bottom communicating with the interior of the casing at the bottom of the valve seat, 60 a spring adapted to raise the valve member from its seat, the valve member being suspended from one end of said spring, a bolt to the inner end of which the other end of said spring is secured, and a stuffing box through 65 which said bolt extends.
9. A valve device adapted to serve as an automatic drain, relief, and "drifting" valve for locomotive and the like engines, comprising a casing having a pair of valve devices arranged therein in proximity to each other, 70 the casing having an internal chamber for each of said valve devices, a valve member mounted in each of said chambers, the bottoms of the respective chambers being shaped complementary to said valves to form seats 75 therefor, the rims of the valve members being so shaped with respect to the chambers as to provide passageways from above the valve members when the same are elevated, a spring for each of said valve members adapted 80 to raise the same from its seat, a pipe connection member extending from one side of the casing and having a port extending to each of the internal chambers above said valve members, each of the valve seats having 85 an annular chamber formed therein, separate pipe connection members extending from the sides of the casing and respectively having ports extending to the annular chambers in the valve seats, the casing having a 90 chamber formed therein below the valve devices and each of said valve devices having a passageway at the bottom constituting a communication between said chamber and the interior of the respective valve devices, and one 95 of the walls of said chamber having an aperture at the end thereof forming a drain passageway from said chamber to the exterior.
10. A valve device adapted to serve as an automatic drain, relief, and "drifting" valve 100 for locomotive and the like engines, comprising a casing having a pair of valve devices arranged therein in proximity to each other, the casing having an internal chamber for each of said valve devices, a valve member mounted in each of said chambers, the lower surfaces of said valve members being frusto- 105 conical in shape and the bottoms of the respective chambers being shaped complementary to said valves to form seats therefor, the rims of the valve members being so shaped with respect to the chambers as to provide passageways from above the valve members when the same are elevated, a spring for each of said valve members adapted to raise the 110 same from its seat, a pipe connection member extending from one side of the casing and having a port extending to each of the internal chambers above said valve members, each of the valve seats having an annular chamber 115 formed therein, separate pipe connection members extending from the sides of the casing and respectively having ports extending to the annular chambers in the valve seats, the casing having a chamber formed therein 120 below the valve devices and each of said valve devices having a passageway at the bottom constituting a communication between said chamber and the interior of the respective valve devices, and one of the walls of said 125 chamber having an aperture at the end thereof forming a drain passageway from said chamber to the exterior.

chamber having an aperture at the end thereof forming a drain passageway from said chamber to the exterior.

11. A valve device adapted to serve as an automatic drain, relief, and "drifting" valve for locomotive and the like engines, comprising a casing having a pair of valve devices arranged therein in proximity to each other, the casing having an internal chamber for each of said valve devices, a valve member mounted in each of said chambers, the lower surfaces of said valve members being frustoconical in shape and the bottoms of the respective chambers being shaped complementary to said valves to form seats therefor, the rims of the valve members being so shaped with respect to the chambers as to provide passageways from above the valve members when the same are elevated, a spring for each of said valve members adapted to raise the same from its seat, a pipe connection member extending from one side of the casing and having a port extending to each of the internal chambers above said valve members, each of the valve seats having an annular chamber formed therein, separate pipe connection members extending from the sides of the casing and respectively having ports extending to the annular chambers in the valve seats, the casing having a chamber formed therein below the valve devices and each of said valve devices having a passageway at the bottom constituting a communication between said chamber and the interior of the respective valve devices, and the side walls of said chamber having apertures at each end thereof forming a drain passageway from said chamber to the exterior.

In testimony whereof, I have hereunto signed my name.

ROBERT H. GEORGE.
